(57) **CLAIM**

The ornamental design for a hanger, as shown and described.

DESCRIPTION

FIG. 1 is a perspective view of a hanger showing my new design, shown in a closed configuration;

FIG. 2 is a front view thereof, the rear view being a mirror image;

FIG. 3 is a top view thereof;

FIG. 4 is a bottom view thereof;

FIG. 5 is a right side view thereof, the left side view being a mirror image thereof;

FIG. 6 is a perspective view of the hanger shown in an open configuration;

FIG. 7 is a front view thereof, the rear view being a mirror image;

FIG. 8 is a top view thereof;

FIG. 9 is a bottom view thereof; and,

FIG. 10 is a right side view thereof, the left side view being a mirror image thereof.

The broken lines shown in the drawing disclosure are for illustrative purposes only and form no part of the claimed design.
